[57] CLAIM

The ornamental design for a fireplace tray for collecting ashes, as shown.

DESCRIPTION

FIG. 1 is a perspective view of a fireplace tray for collecting ashes showing my new design, wherein the broken line showing of the fireplace grate is for illustrative purposes only and forms no part of the claimed design;

FIG. 2 is a top view thereof;

FIG. 3 is a bottom view thereof;

FIG. 4 is a front elevational view thereof;

FIG. 5 is a rear elevational view thereof;

FIG. 6 is a left side elevational view thereof; and,

FIG. 7 is a right side elevational view thereof.
